UNITED STATES PATENT OFFICE.

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY.

BOILER.

Application filed October 5, 1925. Serial No. 60,699.

My invention relates to improvements in heating apparatus and the same has for its object more particularly to provide a boiler in which the complete consumption of the fuel will be smokelessly effected.

Further, said invention has for its object to provide a boiler in which the secondary air required to effect the complete combustion of the fuel is introduced into the boiler at the lowest practical temperature.

Further said invention has for its object to provide a boiler in which the secondary air necessary to effect the complete combustion will, due to its introduction at such relatively low temperature into the combustion chamber containing the relatively lighter hot combustible gases, be caused to attain a high velocity or rate of flow, and be brought more or less forcibly into contact with the bed of incandescent fuel and the hot gases and products of combustion emanating therefrom.

Further, said invention has for its object to provide a boiler in which the secondary air is introduced into the boiler through a transverse duct having a long, relatively narrow outlet, and utilizing the temperature differential between the air in said duct and the gases within the combustion chamber to convert the pressure head of said air into velocity or rate of flow in order to effect the due mixture of said air with the combustible gases to effect complete combustion.

Further, said invention has for its object to provide a boiler in which the secondary air required to effect the complete consumption of the fuel is caused to be discharged into the combustion chamber in the form of a broad band extending transversely entirely across the fuel receptacle adjacent to the rear end of the grate, and brought forcibly into intimate mixture with the products of combustion.

Further, said invention has for its object to provide a boiler in which the secondary air is conducted to a central point within the boiler and then uniformly discharged transversely across the fuel bed and mixed with the products of combustion as the same pass from the combustion chamber to the flues.

Further, said invention has for its object to provide a boiler in which the secondary air is introduced into the boiler by way of a relatively wide transverse duct, extending entirely across the boiler, and having opposing

wall portions oppositely curved to form a constricted outlet producing a Venturi tube action or effect.

Further, said invention has for its object to provide a boiler in which the secondary air is conducted into the boiler and to the central part of a transverse duct having a relatively narrow longitudinal discharge opening therein in order that the volume of air entering said duct may be caused to issue from said discharge opening at high velocity and be projected forcibly, in the form of a downwardly flaring band, against the bed of incandescent fuel and into intimate contact with the combustible gases and products of combustion passing between said duct and the bed of fuel.

Further, said invention has for its object to provide a boiler in which the secondary air is introduced into the boiler from the opposite sides thereof and conducted to a central point within the boiler, and then uniformly discharged transversely across the fuel bed and mixed with the products of combustion as the same pass from the combustion chamber to the flues.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings forming part of this specification, wherein like numerals of reference indicate like parts—

Figure 1, is a front elevation showing one form of boiler constructed according to, and embodying my said invention;

Fig. 2, is a rear end elevation with parts broken away;

Fig. 3, as a vertical longitudinal section on the line 3—3 of Fig. 1;

Fig. 4, is a horizontal section;

Fig. 5, is an enlarged detail perspective view showing the form of the secondary air duct; and

Fig. 6, is a rear end elevation of the boiler.

In said drawings 10 designates a boiler of the sectional type comprising a hollow front section 11, a hollow back section 12, and a plurality of hollow intermediate sections 13. The said front, back and intermediate sections are communicatively connected at their 110

upper and lower portions by nipples 14, in the usual manner.

The front section is provided with the usual flue openings 15, fuel opening 16, slicing opening 17, and ash pit opening 18 which are respectively provided with doors 15^a 16^a 17^a 18^a. The back section is provided with a smoke outlet 19 over which is secured a flanged smokehood 19'.

10 Each intermediate section 13 is here shown in the form of an endless loop having hollow vertical portions 20, forming the side walls of the boiler, and hollow horizontal top and bottom portions 21, 22, respectively. The intermediate sections 13 are further each provided with registering hollow transverse members 23 which jointly form the crown sheet or top of the combustion chamber. Intermediate said transverse members 23 and the top transverse members 21 are the longitudinally extending outer and intermediate flues 24, 24^a and 24^b. The hot gases and products of combustion are caused to pass upwardly at the rear of the combustion chamber into the flues 24 and 24^a, and forwardly therein from the rear of the boiler, and thence rearwardly through the center flue 24^b to the smoke outlet 19.

30 Adjacent to the rear end of the boiler two adjoining intermediate sections 13 are provided with integrally formed depending hollow members 26, which are arranged in spaced relation parallel to each other, and extending entirely across the interior space or combustion chamber at the rear of the grate.

40 The said depending members 26 have their opposing wall portions 27 adjacent to their lower edges curved inwardly towards each other to form a constricted outlet terminating in a gradually flaring mouth which communicates with the secondary air space or flue 28 formed between said depending members 26.

45 The secondary air is admitted through openings 29 at the opposite sides of the boiler and is conducted through the passages 28^a formed in the upper portions of the secondary air space 28 by the horizontal hollow water-backed partitions 26^a integral with and extending from the opposing walls 26. The inner ends of said partitions 26^a are spaced from each other to provide an intermediate opening 30 through which the air is discharged from said passages 28^a into the lower portion 28^b of said air space 28.

60 As the secondary air is admitted into the furnace at a comparatively low temperature, and as the heated gas and products of combustion within the combustion chamber possess a relatively high temperature the secondary air, partly due to said differential in temperature and partly due to the tension of the draft, will be caused to issue under pressure or suction with great velocity and im-

pinge or mushroom upon the incandescent fuel upon the grate directly below said air duct, and thus become intimately mixed with the hot gases and products of combustion as they pass from the combustion chamber to the flues.

65 Further, the secondary air is delivered into the transverse air duct 28^b at a point midway of its ends, and caused completely to fill said duct, as a result of which the air will be discharged evenly and uniformly through the entire length of the constricted outlet, in the form of a continuous sheet through which and with which the hot gases and products of combustion must pass after leaving the combustion chamber, and thus insure the complete combustion of the fuel.

75 The admission of secondary air to the passages 28^a and duct 28^b is controlled by means of the closures 31 hinged at 32 over the openings 29. A sector 33 secured to each closure 31 is engageable with the edge of the opening to permit of the closure being held to different positions of adjustment whereby to control the amount of air admitted through said openings.

80 Having thus described my invention, what I claim and desire to secure by Letters Patent is:

1. A boiler of the character described comprising front, back, and intermediate sections communicatively connected, certain of said intermediate sections each having a depending water containing member communicating with the water spaces of the boiler and arranged parallel in spaced relation to form therebetween a transverse duct having a constricted discharge opening at its base, and horizontal partitions dividing the end portions of said duct to form upper passages open at the outer ends thereof for conducting air to a point intermediate the ends of said duct and discharging the same into the lower portions thereof, substantially as specified.

95 2. In the heating apparatus of the character described, means for supplying secondary air thereto from without comprising a duct having all of its wall portions water-backed and extending transversely across the apparatus above and adjacent to the rear of the fuel bed, and having a longitudinal opening in its under side for directing said secondary air downwardly upon the bed of incandescent fuel and to mingle with the gases and products of combustion as the same are about to pass between said duct and the fuel bed, and horizontal partitions dividing the outer portions of said duct to form upper passages open at the outer ends thereof for conducting the secondary air to a point intermediate the ends of said duct and discharging the same into the lower portions thereof, substantially as specified.

100 3. In a heating apparatus of the character

described, means for supplying secondary air thereto comprising a duct arranged transversely of the apparatus above and adjacent to the rear of the fuel bed and composed of 5 depending water-backed members communicating severally with the water spaces of the apparatus and arranged in spaced relation to one another with their lower edges separated to form a longitudinal discharge opening, 10 and horizontal partitions dividing the outer portions of said duct to form upper passages open at the outer ends thereof for conducting the secondary air from without to a point intermediate the ends of said duct and discharging the same into the lower portions 15 thereof, substantially as specified.

4. In a heating apparatus of the character described, means for supplying secondary air thereto from without comprising a plurality 20 of transverse depending water-containing members substantially coextensive in length with the width of the apparatus communicating at their ends and upper intermediate portions with the water-spaces of the apparatus; said members forming therebetween a duct extending across the combustion chamber above and adjacent to the rear of the fuel bed and having a longitudinal discharge opening at its base, and hollow, water-backed 25 partitions integral with and extending from the opposing walls of said members and dividing the outer portions of said duct to form upper passages open at the outer ends thereof for conducting secondary air to a point intermediate the ends of said duct and discharging the same into the lower portions thereof, substantially as specified.

5. A boiler of the character described comprising a plurality of transverse sections 30 communicatively connected; certain of said sections above and adjacent to the rear of the bed of fuel each having a depending water-containing member communicating with the water spaces of its respective boiler section; said members being arranged in spaced relation to form therebetween a transverse duct having a discharge opening at its base, and horizontal portions extending from the opposing walls of said members and registering 35 at their inner edges with each other to provide partitions dividing the outer portions of

said duct into upper and lower passages; the upper of said passages being open at the outer ends thereof for conducting secondary air from without the boiler to a point intermediate the ends of said duct and discharging the same into the lower of said passages, substantially as specified. 55

6. A boiler of the character described comprising a plurality of transverse sections 60 communicatively connected; certain of said sections each having a depending water containing members communicating at its ends and upper intermediate portions with the water spaces of its respective boiler section; said members being arranged in spaced relation to form therebetween a transverse duct having a longitudinal discharge opening at its base, and horizontal, hollow, water-backed 65 portions extending laterally from the opposing walls of said members and registering at their inner edges with each other to provide partitions dividing the outer portions of said duct into upper and lower passages; said upper passages being open at the outer ends 70 thereof for conducting secondary air from without the boiler to a point intermediate the ends of said duct and discharging the same centrally into the lower of said passages, substantially as specified. 75

7. In a heating apparatus of the character described, means for supplying secondary air thereto comprising a duct arranged transversely of the apparatus above and adjacent to the rear of the fuel bed and composed of 80 depending water-backed members communicating severally with the water spaces of the apparatus and arranged in spaced relation to one another with their lower edges separated to form a longitudinal discharge opening; said duct having superposed parallel passages therein between said depending members; the upper of said passages having air inlet openings at its outer ends, and an outlet opening intermediate of its ends communicating with the lower of said passages for conducting air centrally thereto, substantially as specified. 85

Signed at the city of New York, in the county and State of New York, this 3d day 90 of July, 1925.

ANDRÉ M. MERTZANOFF.
